UNITED STATES PATENT OFFICE

171,273

NECKLACE OR SIMILAR ARTICLE

Marcel Boucher, Eltingeville, N. Y.

Application July 1, 1953, Serial No. 25,744

Term of patent 3½ years

(CL. D45—16)

To all whom it may concern:

Be it known that I, Marcel Boucher, a citizen of the United States, residing at Eltingeville, in the county of Richmond and State of New York, have invented a new, original, and ornamental Design for a Necklace or Similar Article, of which the following is a specification, reference being had to the accompanying drawing, forming part thereof.

In said drawing,

Fig. 1 is a front elevational view of the necklace, showing my new design.

Fig. 2 is a top plan view of the same.

I claim:

The ornamental design for a necklace or similar article, as shown.

MARCEL BOUCHER.
